MARCUS C. HOPKINS, OF WASHINGTON, DISTRICT OF COLUMBIA, ASSIGNOR TO HOPKINS CORPORATION, OF JERSEY CITY, NEW JERSEY, A CORPORATION OF DELAWARE

LOUD-SPEAKER

Application filed February 11, 1926. Serial No. 87,491.

The present invention relates to loud speakers of the type disclosed in my copending application, Serial No. 77,083, filed December 22, 1925. The loud speaker disclosed in that application comprises a central relatively light and stiff diaphragm or tympanum, preferably conical in shape, and a surrounding external sound board or resonator having greater mass than that of the central diaphragm. The connection between the central diaphragm and the external resonator or sound board is such that the central diaphragm will respond to the relatively high frequencies and will efficiently reproduce the high tones or sounds, and the relatively low frequencies will be transmitted through said connection to the sound board so that it will respond to the relatively low frequencies and will efficiently reproduce them. The principal object of this invention is to provide a loud speaker of the foregoing type, the sound board of which is made of synthetic lumber, and by this term I intend to include products of the type of relatively rigid sheets or boards made from fibres that have been separated, in part, at least, and then reassembled in heterogeneous arrangement in a new assembly.

Synthetic lumber has the requisite properties for promoting the regeneration of the relatively low frequencies which are passed on to the sound board or resonator for reproduction. I am not prepared to state exactly what properties of synthetic lumber are responsible for the improved operation of the loud speaker disclosed in this application, but undoubtedly the soft and porous nature of this material and its extreme lightness are contributing factors, and I attach particular importance to the fact that the material is free from grain and has its component fibres and groups of fibres in heterogeneous arrangement.

Several forms of loud speakers in which synthetic lumber may be advantageously employed are disclosed in the accompanying drawings, in which

Fig. 1 is a front view of a loud speaker especially designed for use in hotels, theatres, concert halls and similar places where a large volume of sound is desired;

Fig. 2 is a side elevation of the speaker shown in Fig. 1;

Fig. 3 is a rear view of the loud speaker shown in Fig. 1;

Fig. 4 is a vertical section taken on the line 4—4 of Fig. 3;

Fig. 5 is an enlarged detail vertical section of the central portion of the loud speaker showing the connection between the central diaphragm and the external sound board or resonator.

Fig. 6 is a front elevation of another type of loud speaker operating on the same principle as that shown in Fig. 1;

Fig. 7 is a top plan view of the loud speaker shown in Fig. 6;

Fig. 8 is a rear elevation of the speaker shown in Fig. 6;

Fig. 9 is a vertical section taken on the line 9—9 of Fig. 8;

Referring first to Figs. 1 to 5 inclusive, the loud speaker shown in these figures comprises a central conical diaphragm or tympanum 1 coupled to a vibratory resonator or sound board 2 by means of a semi-flexible coupling, shown in Fig. 5. The conical diaphragm 1 is preferably made of cover paper, cut and folded to shape and glued along a radial seam. Near the outer edge of the cone thus formed, the paper is creased and then folded up to form a forwardly flaring brim 3 (Fig. 5). This brim naturally assumes an angle to the plane of the base equal to the angle between the radial elements of the cone and that base. The outer edge portion of the brim 3 is preferably glued to the inner circular edge of the resonator or sound board 2. For this purpose the inner circular edge of the sound board is tapered as shown at 4 and the outer edge portion of the brim 3 seats upon and is glued to the tapering surface thus formed.

In gluing or cementing the brim to the beveled edge 4 it is important that a part of the brim be left free to form a hinge on which the cone may float. Thus with a brim $\frac{3}{4}$ " wide the cemented portion may have a width of $\frac{1}{4}$ of an inch more or less and the remainder of the brim may be left free to swing.

The resonator or sound board 2 in accord-

ance with this invention, is made of synthetic lumber.

The vibratory actuating force is applied to the apex of the conical diaphragm by means of a rod or wire 5 which is adapted to be

5 maintained in fixed relation with the diaphragm by means of a set screw 6. The rod 5 may be actuated by electromagnetic mechanism housed in the casing 7. The casing 7 may be attached to a support or spider 8 which in turn may be affixed to the resonator or sound board by means of wood screws 9.

10 While the loud speaker shown in Figs. 1 to 5 inclusive may be made of any desired size within reasonable limits, it has been found

15 that for concert work excellent results have been obtained by making the conical dia- phragm approximately 17 inches in outside diameter and the resonator or sound board approximately 4 feet in outside diameter.

20 The relatively large size of the loud speaker shown in Figs. 1 to 5 inclusive makes it de- sirable to suspend it by cords or chains which may be attached to any suitable part of the loud speaker, preferably the spider 8. The 25 loud speaker may be suspended from the ceiling of a room, a bracket or any other support- ing device.

25 The loud speaker shown in Figs. 6 to 9 in- clusive is very similar in construction to that above described. It comprises a conical tympanum 1', a sounding board or resonator 2', a spider 8', for supporting the casing 7' of the electromagnetic actuating mechanism, and a forwardly flaring brim 3' on the cone which is attached to the inner edge of the sound board in the same manner as explained in connection with Figs. 1 to 5. The resonator or sound board 2' of this form of loud speaker is also made of synthetic lumber as in

30 the case of the loud speaker described above.

The main difference between the speaker shown in Figs. 6 to 9 inclusive and that shown in the first five figures is that the sound board 35 or resonator 2' is of smaller diameter. The conical diaphragm 1' may or may not be

40 smaller than the conical diaphragm of the loud speaker of figures 1 to 5. The reduction in overall size of the loud speaker shown 45 in Figs. 6 to 9 inclusive makes it possible to support the speaker on a table or other horizontal surface and for this reason the sound board 2' is provided with suitable legs or cross pieces 10 glued or otherwise fastened to

50 the sound board. The sound board may be provided with an opening 11 to provide a

55 hand grip for moving the loud speaker from one place to another. In constructing a loud speaker of the type shown in Figs. 6 to 9, I

60 have found that excellent results are obtained by making the cone 2' approximately 15½" in diameter and the sound board approximately 22" in diameter. This makes the

65 transverse width of the annular sound board approximately 3½" but good results may be

obtained by making the sound board of even less width than this or of even greater width than the sound board shown in Figs. 1 to 5 in- clusive.

In both types of speaker the central conical diaphragm efficiently reproduces the higher tones and perhaps some of the intermediate tones while the surrounding annular reso- nator or sound board efficiently reproduces the lower or bass notes. By reason of the fact that the sound board is made of synthetic lumber the reproduction of the lower or bass notes is very true and faithful. The lower notes are not only accurately reproduced but the tonal quality is excellent, the reproduction being soft and mellow.

In a loud speaker constructed in accordance with the foregoing description, the regen- erated or reproduced sound waves are sub- stantially directly proportional both quanti- tatively and qualitatively to the actuating force and the sound so reproduced retains substantially the same balance of high and low tones as the original sound from which the actuating force was derived.

In a companion application Serial No. 79,- 329, filed January 5, 1926, I have described and claimed a loud speaker having a sound- ing board made of balsa wood. Loud speak- ers thus equipped give wonderfully accurate 95 sound reproduction with good tonal quality and balance, but the sound boards are difficult to make, particularly if built up as a multiple- ply veneer. Balsa wood splinters and breaks in the ply cutting machines and the cut pieces 100 fray at the edges during handling in the mill. Also the completed board is inclined to warp unless special expedients are resorted to for holding it in shape.

By my present invention there is substi- tuted a sound board material easily obtain- able in the open market at low cost and hav- ing many of the advantages of balsa wood 105 without its disadvantages.

One suitable material is made from bagasse and other fibrous material by separating the fibres of the raw material and then reassembling them in a felted, heterogeneous ar- rangement either with or without the addition of a binder. The material as purchased 110 is relatively light in weight and has an open porous texture with fibres and bundles of fibres of considerable length. These are char- acteristics which I have found desirable in the sound board of an electrically actuated 115 loud speaker.

Another suitable material is made from wood by physically separating the fibres and then, after physical or other treatment, re- assembling them in heterogeneous felted ar- rangement of a relatively rigid nature and of 120 a porous texture as described in United States Patents Nos. 1,631,172 and 1,631,173.

Still another material is made from paper mill screenings, reassembled as described at 130

length in United States Patents No. 1,153,512 and No. 1,187,476.

These three materials are typical of that class of materials which I have chosen to call "synthetic lumber." That of Patents Nos. 1,153,512 and 1,187,476 is the best for general use, but very "brilliant" results may be had from using the material of Patents Nos. 1,631,171, 1,631,172, and 1,631,173. The results with the first mentioned material are acceptable, but the material seems to lack either a stiffness in the individual fibres or a lack of secure attachment between one fibre and its fellows where they cross one another in their heterogeneous arrangement. Individually the fibres should be stiff, and collectively they should rigidly interlock to form a porous rigid mass. Just why that is, I do not know.

20 I claim:

1. A loud speaker tympanum having a portion which is substantially fully responsive to the higher frequencies and a portion consisting essentially of synthetic lumber which 25 is substantially fully responsive to the lower frequencies.

2. A loud speaker tympanum having a sound reproducing rim of synthetic lumber which is substantially fully responsive to the 30 lower frequencies and a portion within said rim which is substantially fully responsive to the higher frequencies.

3. A loud speaker tympanum of the cone type having a sound reproducing rim which 35 is substantially fully responsive to the lower frequencies and consisting essentially of wood fiber reassembled in heterogeneous arrangement.

4. A loud speaker comprising a relatively 40 light and stiff diaphragm, an external synthetic lumber sound board of greater mass than the diaphragm, and a flexible coupling between the two adapted to permit the diaphragm to respond to relatively high frequencies and adapted to transmit the relatively low frequencies to the sound board.

5. A loud speaker comprising a central relatively light and stiff diaphragm, an external synthetic lumber sound board of 50 greater mass than the diaphragm, and a flexible coupling between the two adapted to permit the central diaphragm to respond to relatively high frequencies and adapted to transmit the relatively low frequencies to the sound board.

6. A loud speaker comprising a central conical diaphragm, an external synthetic lumber sound board of greater mass than the diaphragm, and a flexible coupling between the 60 two adapted to permit the conical diaphragm to respond to relatively high frequencies and adapted to transmit the relatively low frequencies to the sound board.

7. A loud speaker comprising a central conical diaphragm, an external synthetic lumber

sound board and a connection between the conical diaphragm and the sound board adapted to permit the central diaphragm to respond to relatively high frequencies and adapted to transmit the relatively low frequencies to the sound board.

8. A loud speaker comprising a central conical diaphragm, a synthetic lumber sound board providing an annular flange or skirt extending radially beyond the conical diaphragm and a connection between the conical diaphragm and the sound board adapted to permit the conical diaphragm to respond to relatively high frequencies and adapted to transmit the relatively low frequencies to the sound board.

9. A loud speaker comprising a central conical diaphragm having an integral forwardly flaring brim portion, and a synthetic lumber sound board providing a flange portion extending radially beyond the conical diaphragm, said forwardly flaring brim portion of the conical diaphragm being attached to the sound board.

10. A loud speaker comprising a conical diaphragm provided with a peripheral corrugation forming a hinge portion, and a synthetic lumber sound board providing a flange portion extending radially beyond the conical diaphragm, said hinge portion being secured to said sound board.

11. A loud speaker comprising a synthetic lumber sound board, and a conical diaphragm flexibly connected thereto so that a portion of the sound board extends radially beyond the conical diaphragm, the flexible connection between the conical diaphragm and the sound board being adapted to permit the conical diaphragm to respond to relatively high frequencies and being adapted to transmit the relatively low frequencies to the sound board.

12. A loud speaker comprising a central conical diaphragm made of paper, an external sound board made of wood fibre reassembled in heterogeneous arrangement and a flexible connection between the two adapted to permit the conical diaphragm to respond to relatively high frequencies and adapted to transmit the relatively low frequencies to the sound board.

13. A loud speaker comprising a synthetic lumber sound board having a central opening, a conical diaphragm mounted in said opening, actuating means for the conical diaphragm, and means for supporting said actuating means comprising a support attached to the sound board and spanning the central opening thereof.

14. A loud speaker comprising an annular flat synthetic lumber sound board having a circular central opening, a conical diaphragm having a circular periphery, said conical diaphragm being mounted in said opening, and a flexible coupling between the conical diaphragm and the sound board adapted to per-

mit the conical diaphragm to respond to relatively high frequencies and adapted to transmit relatively low frequencies to the sound board.

15. A loud speaker comprising an annular synthetic lumber sound board having a central opening the edge portion of which is provided with a tapering seat, and a conical diaphragm mounted in said opening said diaphragm having a forwardly flaring frusto-conical brim portion secured to the sound board on said tapering seat.

16. A loud speaker comprising a flat annular sound board made of wood fibre reassembled in heterogeneous arrangement, said sound board having a central opening the edge portion of which is provided with a tapering seat, and a fibrous conical diaphragm mounted in said opening and having an integral forwardly projecting brim portion, a part of said brim portion being attached to the sound board at said tapering seat.

In testimony whereof I affix my signature.
MARCUS C. HÖPKINS.
